C. O. Wilson By their attorney A. B. Stoughton.

United States Patent Office.

JOHN GROSS AND JOHN C. TUNISON, OF DECATUR, ILLINOIS,

Letters Patent No. 72,027, dated December 10, 1867.

IMPROVEMENT IN CULTIVATORS.

The Schedule referred to in these Letters Patent and making part of the same.

TO ALL WHOM IT MAY CONCERN:

Be it known that we, JOHN GROSS and JOHN C. TUNISON, of Decatur, in the county of Macon, and State of Illinois, have invented certain new and useful Improvements in Cultivators; and we do hereby declare the following to be a full, clear, and exact description of the same, reference being had to the accompanying drawings, making a part of this specification, in which—

Figure 1 represents a top plan of the cultivator, and

Figure 2 represents a longitudinal vertical section through the same.

Similar letters of reference, where they occur in the separate figures, denote like parts of the machine in both of the drawings.

Our invention consists, first, in the combination and combined action of the two frames, which act together and independent of each other, so that when the ploughs, which are attached to one of the frames, come in contact with any obstruction that might otherwise break or injure them, the other frame will move forward, and thus relieve the ploughs from the suddenness of the jay or stoppage.

And our invention further consists in the use of a frictional or spring-hook, connected to the tongue or its frame, by which the two frames are united, and made one, as it were, until the resistance or pressure on the ploughs exceeds that of the frictional or spring-hook, when the two frames are separated, and one may remain obstructed whilst the other is drawn forward, as will be explained.

To enable others skilled in the art to make and use our invention, we will proceed to describe the same with reference to the drawings.

A is an axle, supported in the two carrying-wheels B B, and upon this axle is firmly fixed a frame, C, which we term the "back frame," which carries the driver's seat D. There is a second frame, E, which can move upon the axle or back frame, and upon this second frame, which we term the "front frame," are attached the tongue F and the ploughs G and H. These ploughs are pivoted, at their upper ends, to the "front frame" E, and a chain, a, connected to the front ploughs, passes around a pulley, b, on said front frame, and is then united to the back frame. A rod, c, connects each of the rear ploughs with the chain, so that if any plough of the series or two pairs should strike a stone or other obstruction, it would stop the front frame, and the onward motion of the team would only draw the rear frame forward upon the front frame. Upon the under rear side or end of the tongue F there is a hook, 2, upon the shank of which there is a coiled spring, 3, and a nut, 4, by which said spring may be regulated. This hook catches upon the cross-bar C' of the back frame, and thus unites the two frames. When, however, the resistance upon any one or more of the ploughs exceeds the force with which the hook holds, it (the hook) lets go or is released, and then the back frame, through the chains a, will move forward on to the one thus held back, and this saves the breaking or injuring of the ploughs or of the machine. When the "rear frame" has thus been drawn up or forward upon the other or "front frame," and the operator desires to put the machine again in working condition, he presses down upon the lever e, which allows the frames to assume their working positions, and the hook takes on to and holds the two frames together until another obstruction comes in the way, and they again detach, and thus prevent breakage. The front ploughs G are hung to a bar, d, which, in turn, is attached to pivoted or swinging arms, f, upon which foot-rests, g, are placed, so that the driver, in his seat, may move these front ploughs to either side, so as to escape stalks out of line or of the rows. The dotted and the red lines, in addition to the black lines, show all the moving parts in their two positions.

Having thus fully described our invention, what we claim therein as new, and desire to secure by Letters Patent, is—

1. The arrangement and combined action of the two frames, so that when any permanent obstruction comes against any of the ploughs, the frames will disconnect, and the back frame ride or move up on the front one, and thus avoid breakage, substantially as described.

2. We also claim a frictional spring-hook upon the tongue or tongue-frame, for catching and holding upon the cross-bar of the "rear frame," so that the two frames will not disconnect until the pressure upon the ploughs or ploughs exceeds that for which the hook has been adjusted, substantially as described.

JOHN GROSS,
JOHN C. TUNISON.
